UNITED STATES PATENT OFFICE.

ORAZIO ANTONELLI, OF BROOKLYN, NEW YORK, ASSIGNOR, BY MESNE ASSIGNMENTS, TO RECREATOR PHONOGRAPH CORPORATION, OF BOSTON, MASSACHUSETTS, A CORPORATION OF MASSACHUSETTS.

PROJECTING MACHINE.

Application filed February 12, 1921. Serial No. 444,547.

My invention relates to projecting machines, and aims to provide certain new and useful improvements in connection with a device of this character.

It is a well appreciated fact that any number of attempts have been made to provide a system which will permit of the projection of pictures upon a screen, and also provide sound reproduction which would synchronize with the movement of the figures depicted by the projecting apparatus, to permit of a clearer visualization of the performance being rendered.

These devices for the most part have proven impractical in that great difficulty has been experienced in properly synchronizing the movement of these two different apparatus working in unison, aside from the expense involved, it being noted in this connection, that the apparatus embodied for producing the effect desired, is, in most instances very complicated, and involved the outlay of considerable expense in both its installation and maintenance.

Also although it might prove of commercial advantage to produce a unit of the nature aforescribed, which would be capable of use in the home, it has been impractical to endeavor to place such a unit upon the market in view of the complication of the parts of the same and their relatively great cost.

Entirely aside from the foregoing, it is also well understood that great difficulty has been experienced in connection with projecting machines in that it has been necessary to utilize a delivery and receiving reel, as well as actuating mechanism for the film which would permit of a projection of pictures simulating motion. Thus the latter apparatus has also involved a relatively great outlay, it being also noted in this connection that it has been necessary to utilize a film of a relatively great length to insure an intelligent reproduction.

Having these defects in mind, it is a primary object of my invention to provide a projecting machine preferably associated with a sound reproducing unit in such a manner that the movement of these two elements will be properly synchronized.

A further object of my invention is the production of a device of this character in which all complication will be eliminated

and by means of which an article may be placed upon the market suitable for home use, and at a nominal figure.

Another object of my invention is the construction of a projecting machine which shall be simplified in such a manner as to insure reliability of operation and the elimination of complication.

Still another object of my invention is the construction of a device of the character stated in which a novel type of film may be employed eliminating a great amount of the bulk of the usual film, although insuring an intelligent and relatively long reproduction.

Further objects of my invention will appear in the annexed specification and drawings which latter present one practical embodiment of my invention, and in which:

Figure 1 is a sectional side view taken through a device constructed in accordance with my invention, and taken along the lines 1—1 of Figure 2.

Figure 2 is a partly fragmentary plan view thereof.

Figure 3 is a partly fragmentary sectional plan view taken through a projecting machine embodying my improved construction.

Figure 4 is an enlarged sectional view taken along the line 4—4 and in the direction of the arrows indicated in Figure 3.

Figure 5 is a fragmentary sectional side view taken along the line 5—5 in the direction of the arrows also indicated in Figure 3.

Figure 6 is a view similar to Figure 5, but showing the parts in slightly different position, and

Figure 7 is a front view of a projecting machine and showing my improved type of film applied thereto.

Referring now more particularly to Figures 1 and 2, it will be seen that, according to my improved construction, and with a view of providing a unit utilizing a projecting and sound reproducing unit I aim to employ a sound reproducing unit in the nature of a phonograph, and a projecting machine of my improved construction, hereinafter more fully described, these elements being properly coupled one to the other, to properly synchronize the motion of the same.

It is also to be noted that if the device is employed for home use, and to further elimi-

nate complication, that I also further preferably utilize a part of the sound reproducing mechanism as a surface against which the light rays of the projecting machine 5 may be directed.

Thus referring more particularly to Figure 1, it will be seen that the reference numeral 10 indicates the cabinet of a conventional reproducing machine, having a lid 11, 10 and enclosing a turntable 12 driven in the usual manner by mechanism 13 through a spindle 14, and also having a co-operating tone arm 15 for the conventional purpose.

It will be noted, however, that a shaft 16 15 is provided, which shaft is coupled to the operating mechanism 13 by any suitable means such as a beveled gear 17, co-operating with a similar gear 18, associated with the turn table 12. The shaft 16, as has 20 been indicated in Figure 2, also provides gears 19 serving to operate a projecting machine 20.

Thus it will be seen that a single source 25 of power serves to operate both the turn table of the talking machine, and the projecting machine, and it will be noted, attention being had to Figure 1, that the lid 11 serves a practical function, in that the under surface of the same may be disposed at 30 an angle at which it will act as a screen for the light rays emanating from the projecting machine.

From the foregoing it will be appreciated 35 that the two units (the sound reproducing and projecting) are synchronized in movement and power driven, and that the entire structure presents an extremely compact appearance in that the lid 11 dispenses with the necessity of providing an extraneous 40 screen serving as a reflecting surface against which the pictures may be projected.

Referring now more particularly to the 45 details of the projecting machine structure, it will be noted reference being had to Figures 3 to 7, that the same includes a drum 21, enclosing a source of illumination 22, the rays of which pass through an opening 23 arranged between the reflecting surfaces provided by the lid 11, and the source of illumination 22.

Also disposed within the body of the drum, are a pair of levers 24 swingingly and slidingly mounted as at 25 adjacent one of their ends, their opposite ends preferably including a quadrangular guide way 26.

An element in the nature of a comb 27 is mounted between the outer ends of the levers 24, and the teeth 28 of this comb extend through slots 29 formed through the 60 body of the drum 21.

A shaft 30 has one of its ends projecting beyond the drum, and co-operates by means of the gear 31 with the gear 19 of the shaft 16. Thus upon the turn table 12 being rotated 65 it will be obvious that a rotation of

the shaft 30 will be effected. The shaft 30 mounts cams 32 which latter are disposed one within each of the guide ways 26, and it will thus be noted that a movement is imparted to the comb 27 which will primarily 70 be outward as in Figure 4, upward, rearward and downward as in Figure 5, downward and outward as in Figure 6, subsequent to which the parts will again assume the position illustrated in Figure 4. 75

Assuming now that a film is looped over the drum 21 and that such film is provided with perforations capable of aligning with the teeth 28 of the comb 27 it will be seen that such a film would be moved with respect 80 to the drum and intermittently, as is necessary to produce the allowance of a constant motion by a projected picture.

This function is to be predicated upon the 85 fact that the teeth 28 will engage with the perforations of the film, move the same upwardly from the position illustrated in Figure 6 to that in Figure 4, and beyond this position, subsequent to which the teeth of the comb would disengage the perforations, 90 and be moved rearwardly and downwardly so that they again might occupy the position illustrated in Figure 6 to repeat the entire operation.

As in ordinary projecting machines, a 95 shutter is necessary to interrupt the projection of the light rays during that brief interval in which the film is being bodily shifted, and thus I conveniently mount a shutter 33 in advance of the source of illumination 22, such shutter being coupled as 100 at 34 with the shaft 30 insuring a proper operation of the parts.

To now furnish a proper film for use in connection with my projecting machine, and 105 at the same time to avoid difficulties incident to projecting machines noted in the preamble of this specification, attention is invited to Figure 7. In this view it will be noted that the film includes a body portion 35 110 formed with perforations 36, the ends of the body portion 35 being pasted or otherwise secured with respect to each other to form an endless member. In this connection it is to be noted, however, that the side edges 115 of the ends of the body portion 35 are not brought into alignment with each other, but that these ends are off-set, as has been clearly indicated in the figure referred to.

Thus the opening 23 being of a size equal 120 to the area of the film to be exposed, at one time, it will be seen that the body of the film 35 will be fed past the opening 23, and this operation will be continued to a point 125 at which the end of the body 35 is reached. Instead, however, of the part of the film just projected being repeated, it will be noted that the second row of pictures upon the film will be projected, and this operation will be repeated until finally the rear 130

off-set end of the body portion 35 is moved beyond the opening 23.

With a view of accommodating the movement of the film in not alone a downward or upward plane, but also in a transverse movement it will be noted that the drum 21 is of a width sufficient to permit of this being accomplished, and to retain the body 35 in proper position upon the drum, the 5 guide bar 37 may be hingedly secured as at 38 to the drum 21 and be clamped in proper spaced relationship thereto by any suitable means such as 39, it being noted that slots 40 are provided into which the teeth 28 of 10 the comb 27 may project to move the film bodily.

Thus it will be seen that I have provided, as a single unit, a sound reproducing and projecting mechanism which although not 20 limited to this particular purpose is ideally adapted for home use, and in which all complication has been eliminated, although the elements are perfectly synchronized in operation.

25 It will also be noted that an improved projecting machine is provided, which of course may be used independently of the sound mechanism, which is ideally adapted for use in that it eliminates all complication in connection with the feeding, receiving and projecting of the film.

Also by virtue of the improved type of film provided, by means of my invention, it will be noted that the conventional feeding and receiving reels may be dispensed with and that although an endless film is provided, that the same will permit of a projection for a relatively great length of time.

40 Obviously numerous modifications of structure might readily be resorted to without in the least departing from the spirit of my invention, which I claim as—

45 1. The combination with an endless relatively wide film band, having pictures arranged thereon in a continuous spiral line and equipped with feeding perforations also arranged in a spiral line corresponding to said picture line and bordering the same throughout, of a support relatively elongated with respect to the width of such film band over which the film band is adapted to slide and also move laterally, and operating means associated with said support, 50 adapted to engage the perforations of the film band to advance the same, and by such engagement to also feed the film band laterally upon said support, whereby the spiral picture line on the film band is caused to traverse a given line of picture projection.

55 2. The combination of an endless relatively wide film band having pictures arranged thereon in a spiral line, a support upon which said band is adapted to rest and slide, said support being relatively

elongated with respect to the width of the film band, and operating means associated with said support arranged for intermittent engagement with the film to advance the same, said operating means and said film 70 band having interengaging parts for imparting movement from the former to the latter, said operating means being adapted to advance the film band and move the same laterally through the medium of said interengaging parts, whereby the spiral picture line thereon is constantly in the given path of picture projection.

3. The combination with an endless relatively wide film band, bearing pictures disposed in a spiral line extending there-around and substantially throughout the width thereof, said band equipped with provision also arranged in a spiral thereon corresponding to the spiral picture line for 80 engagement by an operating device, and an operating device engaging said film band to advance the same and adapted by such engagement to simultaneously move the same lateraly causing said spiral picture line to traverse throughout a given path of picture projection.

4. The combination with an endless relatively wide film band, bearing pictures arranged in a spiral line thereon, and with 85 feeding perforations also arranged in a spiral line bordering such picture line throughout the same, of a support upon which the film band is adapted to slide, relatively elongated with respect to the width of the film band, picture projecting means associated with said support, and feeding means also associated with said support, adapted to engage said perforations of the film band to advance the same 90 and by such engagement to also move the film band lateraly to present the spiral picture line thereon constantly in the path of picture projection by said projecting 95 means.

5. The combination with an endless relatively wide film band, bearing pictures arranged in a spiral line thereon, and with 100 feeding perforations also arranged in a spiral line bordering such picture line throughout the same, of a support upon which the film band is adapted to slide relatively elongated with respect to the width of the film band, picture projecting means associated with said support, and feeding means also associated with said support, 105 embodying a comb extending lengthwise of said support, equipped with teeth projecting through openings of said support to engage said perforations of the film band for 110 advancing the same, and adapted by such engagement to also move the film band lateraly and present the spiral picture line thereon constantly in the path of picture 115 projection of said projecting means.

6. A motion picture projecting machine comprising a relatively elongated housing presenting a top portion curving in cross section and formed with a line of slots spaced apart horizontally, an endless relatively wide film adapted to rest and slide upon the curved top of said housing, and means within said housing extending through said slots for engaging said film and moving the same progressively forward, said film equipped with provision to be moved laterally also by such engagement. 75
- 10 7. A motion picture projecting machine comprising a relatively elongated housing presenting a top surface curving in cross section and provided with a line of horizontally spaced apart slots, an endless film adapted to rest and slide upon the curved top of said housing and to depend therefrom, and a comb formed with teeth, said teeth adapted to extend through said slots to engage the film and move the same forward, said film equipped with provision to receive a component of lateral movement by such engagement. 80
- 15 8. A motion picture projecting machine comprising a relatively elongated housing presenting a top area curving in cross section with a source of illumination within said housing, and said housing formed with an opening for the projection of such illumination, an endless relatively wide film resting upon the curving top surface of the housing, said housing being also formed with slots, and means extending through said slots for engaging said film and moving the same bodily forward, said film equipped with provision to receive a component of lateral movement by such engagement. 85
- 20 9. A motion picture projecting machine comprising a relatively elongated housing presenting a top surface curving in cross section and formed with an opening, a source of illumination within said housing for projecting through such opening, an endless film fitted to slide upon said housing, said housing being also formed with a row of slots spaced apart horizontally, a comb formed with teeth adapted to extend through said slots for engaging said film, and means for moving said comb to advance said film, the film having provision to receive a component of lateral movement by such engagement of the comb therewith. 90
- 25 10. A projecting machine, including a pair of spaced apart levers, means slidably and rockingly mounting said levers, guide-ways forming a part of said levers, a rotatable shaft passing through said guide-ways, cams mounted upon said shaft and moving said guide-ways, and a comb extending between said levers and secured to the outer ends thereof, a drum enclosing said levers and being formed with openings through which the teeth of said comb may extend. 95
- 30 11. A projecting machine, including a pair of spaced apart levers, means slidably and rockingly mounting said levers, guide-ways forming a part of said levers, a rotatable shaft passing through said guide-ways, cams mounted upon said shaft and moving said guide-ways, a comb extending between said levers and secured to the outer ends thereof, a drum enclosing said levers and being formed with openings through which the teeth of said comb may extend, a source of illumination also within said drum, and a movable shutter arranged in advance of said source of illumination and adapted to have portions of its body intermittently interposed between the same and an opening in said drum. 100
- 35 12. A projecting machine, including a pair of spaced apart levers, means slidably and rockingly mounting said levers, guide-ways forming a part of said levers, a rotatable shaft passing through said guide-ways, cams mounted upon said shaft and moving said guide-ways, a comb extending between said levers and secured to the outer ends thereof, a drum enclosing said levers and being formed with openings through which the teeth of said comb may extend, a source of illumination also within said drum, a movable shutter arranged in advance of said source of illumination and adapted to have portions of its body intermittently interposed between the same and an opening in said drum. 105
- 40 13. A projecting machine, including a pair of spaced apart levers, means slidably and rockingly mounting said levers, guide-ways forming a part of said levers, a rotatable shaft passing through said guide-ways, cams mounted upon said shaft and moving said guide-ways, a comb extending between said levers and secured to the outer ends thereof, a drum enclosing said levers and being formed with openings through which the teeth of said comb may extend, a source of illumination also within said drum, a movable shutter arranged in advance of said source of illumination and adapted to have portions of its body intermittently interposed between the same and an opening in said drum, and means secured to said shaft for moving said shutter. 110
- 45 14. An endless and relatively wide film band bearing a series of pictures arranged in a continuous spiral path with rows of feeding perforations bordering such spiral picture path at each side and throughout the extent thereof. 115
- 50 15. An endless and relatively wide film band, bearing a series of pictures arranged in a spiral path extending therearound and substantially from side to side thereof with feeding perforations arranged in a spiral line corresponding to the spiral path of such picture series. 120
- 55 16. An endless and relatively wide film band, bearing a series of pictures arranged in a spiral path with such spiral path bordered by feeding perforations substantially throughout the extent thereof. 125
- 60 17. The combination with an endless relatively wide film band, bearing a series of pictures arranged thereon in a spiral path 130

with such path bordered by spirally disposed feeding perforations, of an operating device therefor embodying a comb presenting a series of teeth spaced apart to engage 5 simultaneously in said perforations and mechanism for actuating said comb to move the teeth thereof first outwardly into engagement with the film band, then forwardly to advance the same, then inwardly 10 out of engagement with the film band, and then rearwardly to initial position.

18. A motion picture apparatus comprising a casing, projection means carried thereby and means in said casing for operating a 15 motion picture film step by step around the same in operative relationship to the said projection means and co-operating spirally arranged guiding means cooperating with

said step by step feeding means to produce a feed of the film by a longitudinal as well 20 as a transverse motion at each step and acting for the transverse movement by direct engagement with the film.

19. In a motion picture apparatus the combination with an endless film provided 25 with perforations arranged in a spiral line, of means for supporting said film to permit it to be moved slidingly on the said surface longitudinally as well as transversely with respect to a spiral row of pictures thereon 30 and feed sprockets adapted to engage the spiral row of perforations at the opposite edges of the film and at an intermediate point during the whole sidewise traverse of the film in moving spirally.

ORAZIO ANTONELLI.
